PERISCOPE SEAL

Walter J. Gilbert, Sr., Indiana, Pa., assignor to
Syntron Company, Homer City, Pa., a corpora-
tion of Delaware

Application October 9, 1947, Serial No. 778,972

9 Claims. (Cl. 286—26)

1

This invention relates generally to seals between concentric members having relative rotary and longitudinal movement therebetween and more particularly to seals for use on submarine periscopes.

The principal object of this invention is the provision of a seal for use on the inner concentric tubular member of a periscope which permits it to be rotated and moved axially of the stationary member and which will prevent the leakage of water at variable pressures during the operation of the periscope.

Other objects and advantages appear herein-after in the following description and claims.

A practical embodiment illustrating the principles of this invention is shown in the accompanying drawings wherein:

Fig. 1 is a view in vertical section showing the stationary tube with the periscope tube mounted therein together with the seal mounted on the form;

Fig. 2 is a plan view of the seal mounting plate assembly shown in Fig. 1.

Referring to the drawing, 1 represents the stationary tube which is rigidly secured in sealed relation with the hull of the ship. The lower end of the stationary tube 1 is provided with a uniform annular face 2 having a series of spaced longitudinally disposed threaded openings 3 for receiving the studded bolts 4 which project beyond the lower face 2 of the tubular member 1.

The plate assembly which carries the annular sealing member consists of the ring-shaped bottom plate member 5 together with the ring-shaped top members 6 which have the same external diameter, the top plate being of less thickness and providing a cap, the upper surface of which abuts against the finished surface 2 on the lower end of the tubular stationary member 1. Each of the rings 5 and 6 are provided with suitably aligned openings 7 and 8 for receiving the studded bolts 4 which bolt them in assembled relation to the tube 1.

The bore of the bottom plate 5 is provided with an upwardly open annular trough 10 which is approximately one fourth the depth of the bottom plate but is spaced from the lower end thereof. The bore of the flange 11, which forms the lip of the trough 10, provides the smallest diameter bore of the bottom plate ring 5. Below the trough 10 the bore of the ring 5 is beveled as indicated at 12. The top surface 13 of the flange 11 is arranged to carry the annular sleeve member 14 by means of its radially extending flange 15, the under surface 16 of which is ar-

2

anged to engage the top surface of the annular flange 11. The radial flange 15 of the sleeve 14 projects over the trough 10 and is provided with clearance between its outer surface and the larger bore 17 of the bottom plate rings 5.

The upper surface of the annular flange 15 is also provided with an annular trough 18 defined by the upwardly extending annular tip 19. From the trough 18 to the upper end of the sleeve 14 the outer surface of the latter slopes toward the external surface of the periscope 20 and is serrated as indicated by the interrupted pockets or grooves 21. The trough 18 and the external serrated surface 21, which join on the outer surface of the sleeve 14, are arranged to receive the sealing member 22 which may be vulcanized or otherwise secured to the sleeve 14 and is constructed from any suitable elastomer such as natural or synthetic rubber or other suitable plastic material, all of which are capable of withstanding salt water and a grease lubricant.

The sealing member 22 has projections which fit in the grooves 21 and a foot that fits into the groove 18. The upper end of the sealing member 22 extends materially beyond the upper end of the sleeve member 14. The bore of this sealing member 22 would normally be out of contact with the periscope tube 20 if it were not held in place by means of the annular garter spring member 23 which fits in the groove 24 formed on the outer surface of the sealing member 22. If the garter spring 23 is removed the upper portion of the rubber sealing member becomes a free body and will tend to flare outwardly as illustrated in dotted lines at 25 in Fig. 1. The groove 24 is formed between two spaced radially disposed flanges 26 and 27 which extend annularly around the upper end of the sealing member 22. The outer surface of the sealing member 22 increases in diameter as illustrated at 28 as it approaches the flange 15 of the sleeve 14. Said surface includes a flat annular surface as illustrated at 29 for the purpose of receiving the retaining band or hoop 31 which is preferably constructed as a continuous annular metal band that may be forced on the annular surface 30 of the sealing member 22 restraining the same under initial compressive force against the periscope tube 20. The hoop 31 rests against the shoulder 32 and the perimetral surfaces of this hoop is sufficiently small in diameter so as not to have clearance with the stationary parts when the periscope tube 20 is rotated.

The annular foot of the sealing member 22 that is positioned in the groove 18 of the sleeve 14 is

arranged to carry an annular wearing ring 33, the top surface of which is extended radially outwardly and is arranged to mate in sealing contact with the corresponding surface 34 on the underside of the top plate member 6, the latter being secured to the bottom plate member 5 by means of the screws 36 which clamp the two members together with a gasket 37 therebetween. The annular sealing surface 34 on the underside of the top plate 6 represents the stationary sealing surface against which the wearing ring 33 bears in rotary sealing engagement. When the screws 36 are tightened on the gasket 37 to direct the upper and lower plates together and on the flange 15 of the sleeve and properly position the wearing ring 33 at the proper gauge thickness relative to the gaskets 37 and determine the deformation of the foot of the packing element 22, this adjustment determines the pressure between the relative rotary sealing surface of the wearing ring and the top plate.

The groove 10 within the bore of the lower plate is provided with an inner sealing ring member 38 which is retained by a metallic band 39 disposed within the annular recess formed in the outer perimetral surface of the sealing member 38. This sealing member is likewise made of a suitable elastomer material such as that employed for constructing the sealing member 22. The flanges 40, formed by the recess 41 in the seal member 38, are constructed to flare axially outwardly so as to provide an initial pressure against the bottom of the groove 10 and the undersurface of the flange 15 on the sleeve 14 between which there is relative rotary motion. In view of the fact that the packing member 38 is held by a band against the inner surface of the flange 11 the packing remains stationary and relative movement is provided between the upper flange of the packing member and the undersurface of the flange 15 of the sleeve 14. Thus, any leakage of liquid passing the sealed wearing ring 33 will be entrapped by the expandable packing ring 38.

It is preferable to prevent any relative rotary movement between the sleeve 14 and the periscope tube 20. To provide a closed fit between the periscope tube 20 and the sleeve 14 a tight fitting wedge sleeve 42 is secured to the bore of the sleeve by means of the screws 43. This frictional engagement, together with the frictional engagement created by the packing member 22, prevents relative rotary movement between the sleeve and the tube. However, the tube 20 is arranged to move axially of the sleeve when adjusting the periscope for different elevations. In order to maintain a smooth and uniform movement between the periscope tube and the sleeve 14 with its packing, an annular groove 44 is provided in the undersurface 16 of the flange 15 which groove is arranged to open to the vertical passageway 45 that connects the radial passageway 46 to a grease gun fixture 47 on the outer side of the lower plate 5. The groove 44 is also connected by means of a passageway 48 to a point at the apex of the sleeve 14. It will be noted that between the end of the sleeve 14 and the packing member 22, a small annular space 50 is provided to receive the grease that is forced through these passageways by means of a pressure lubricating gun. Thus, when the annular space 50 is maintained full of lubricant under pressure, it will be uniformly distributed over the surface of the telescope permitting the latter to readily slide up and down through the sleeve and

its packing. It is usually only necessary to apply grease to lubricate the inner surface of the seal during the use of the periscope. In lubricating the periscope the grease under pressure merely counteracts a portion of the pressure created by the garter spring 23 that compresses the outer end of the packing 22 on the periscope tube.

This seal provides a substantially water-tight joint which permits the periscope tube to be readily adjustable by relative rotation as well as longitudinal movement.

I claim:

1. In a seal the combination of an outer tubular member and an inner coaxially concentric cylindrical member having relative rotary and longitudinal movement therebetween, spaced opposed annular metallic sealing surfaces carried in the bore of the outer tubular member and in sealing relation therewith, a metallic sleeve having a sliding fit on the perimetral surface of the inner cylindrical member, a radial flange on said sleeve extending between said spaced annular surfaces and seated for rotation on one of said surfaces, an annular sealing element of elastomer material carried by said sleeve and flange and extending beyond one end of the sleeve, ring means carried by the elastomer sealing element to retain it in sealed relation with the sleeve and the inner cylindrical element but permitting the latter to move axially thereof, and a metallic wearing ring wholly supported by the elastomer sealing element and engaging said other annular metallic sealing surface to permit relative rotary movement but prevent leakage of fluid therebetween.

2. A seal for the movable tube of a periscope on a ship's hull which consists of a stationary ring sealed with the ship's hull and having spaced inwardly extending annular shoulders, a periscope tube, a sleeve having relative slidable movement on the tube and within said ring and having an integral annular radial flange extending between and having one side engaging one of the shoulders of the ring, an annular elastomer sealing element mounted on the other side of said flange in sealing engagement with the tube and the sleeve, and a wearing ring carried by the elastomer sealing member and engaging the other of said shoulders.

3. A seal for the movable tube of a periscope on a ship's hull which consists of a portable stationary ring mounted in sealed relation on the ship's hull, spaced upper and lower inwardly extending annular shoulders on said ring, a periscope tube passing through the ring, a sleeve having relative sliding engagement on the tube and having a radial integral annular flange bearing on the lower shoulder, an elastomer sealing element mounted on the top of said flange and sealing with said tube and said sleeve, and a metallic wearing ring carried by the elastomer member and bearing against said upper shoulder.

4. A periscope tube seal consisting of a stationary member comprising an upper ring and a lower ring arranged to be mounted in sealed relation to the ship's hull, the upper ring extending inwardly and upwardly to form an annular shoulder, an inwardly and upwardly extending annular shoulder on the lower ring in spaced relation to the shoulder formed by the upper ring, a periscope tube movable in said rings, a sleeve slidably mounted on the periscope tube, a radial flange on the sleeve extending between said upper and lower shoulders and journaled on the latter, tubular elastomer means seated on the top of the shoulder and extending beyond the upper end of the sleeve,

a wearing seal ring carried by the tubular elastomer means and engaging the under side of the upper shoulder, and means to engage the elastomer and hold it in initial pressure engagement with the periscope tube.

5. The structure of claim 4 characterized in that the upper end of the sleeve and the elastomer member have complementary conical surfaces.

6. The structure of claim 4 characterized in that the upper end of the sleeve and the elastomer member have complementary conical surfaces, which are provided with interlocking sections.

7. The structure of claim 4 which also includes a second elastomer ring mounted with initial compression between the under side of the flange and the outwardly extending portion of the lower shoulder.

8. The structure of claim 4 which also includes grease fitting means and connecting passageways for conducting lubricant from the lower ring

5
through the Journal of the sleeve to the surface of the periscope tube.

9. The structure of claim 4 which also includes a retaining band on the elastomer member to hold it on the sleeve.
